UNITED STATES PATENT OFFICE.

FRANCIS H. WILLIAMS, OF BOSTON, MASSACHUSETTS.

PLIERS.

1,427,668.

Specification of Letters Patent. Patented Aug. 29, 1922.

Application filed September 14, 1920. Serial No. 410,230.

To all whom it may concern:

Be it known that I, FRANCIS H. WILLIAMS, a citizen of the United States, and resident of Boston, county of Suffolk, Commonwealth 5 of Massachusetts, have invented an Improvement in Pliers, of which the following description, in connection with the accompanying drawings, is a specification, like characters on the drawings representing like parts 10 in each of the several views.

This invention relates to hand tools and more particularly to tools of a plier or wrench type. As herein illustratively shown the invention is embodied in a parallel-jaw type of pliers. A principal object of the invention is to so modify the jaws of a pair of pliers or like tool that the tool is well adapted to serve also as a hand vise to hold small articles requiring filing or other 20 machining. In accordance with my invention the jaws are so modified as to provide adequate clearance for a file or other operating tool in working on a piece clamped in the plier jaws, and by reason of the modified 25 form of such jaws, the workpiece may be held securely in a diagonal or inclined position therein without requiring more than a shallow or narrow bite of the jaws upon the work piece. A further object is to provide 30 means cooperating with the plier handles adapted to hold the jaws in clamping engagement with a workpiece as long as may be needed, without requiring manual pressure upon the handles for this purpose. The foregoing and other objects and advantages of 35 the invention will more clearly appear from the following detailed description, and the distinctive features of novelty will be thereafter pointed out in the appended claims.

40 Referring to the drawings:

Fig. 1 is a side elevation of a pair of pliers embodying the invention.

Fig. 2 is a similar view showing the handle engaging device in operative position.

45 Fig. 3 is an edge view of the tool.

Fig. 4 is a detail section on line 4—4 of Fig. 1; and

50 Fig. 5 is a perspective view showing the operative end of the tool and illustrating the utility of the modified form of jaws thereof.

55 10 indicates a pair of pliers which may be of any usual or suitable construction, being herein shown as a parallel-jaw type with handles 10^a 10^b pivoted together at 10^c and connected with the respective parallel-jaws

10^d 10^e. The jaws 10^d 10^e have their extremities beveled off at one corner as indicated at 11. This is for the purpose of permitting a secure and reliable grip upon a workpiece 60 with only a narrow or shallow hold thereon as fully explained in my prior application, No. 386,276, filed June 3, 1920. As explained in said earlier application, this beveling off of the jaw corners is of great benefit 65 and advantage for a variety of uses, such as engaging relatively thin nuts lying close to a backing surface and in cases where the bolt through which the nut passes projects to a considerable extent therefrom. In the 70 use of the tool to engage a workpiece extending diagonally with respect thereto, these beveled corners provide a greatly increased area of grasping surface, thereby giving a firmer hold on the workpiece with a relatively narrow engagement of the jaws upon the workpiece. As further explained in said 75 earlier application, the invention as applied to a plier tool is of value and importance in rendering the pliers adaptable for use as 80 a hand vise to clamp and hold workpieces without requiring more than a narrow grip thereon, for filing or other machining. I have found that in adapting the invention to this use, the tool is rendered better adaptable for operating on workpieces that project only a small distance from the jaws, by having an edge of one of the jaws beveled off backward from the corner bevel. Such a beveled edge is indicated at 12 on 85 the upper face of a right hand jaw, this being the form suitable for right handed users and affording clearance for a file F or like tool in the right hand of the user while he is grasping the pliers with his left hand. 90 For left handed users the top face of the other jaw might of course be correspondingly beveled off. It is to be observed that neither this bevel 12 of the jaw H nor the bevel 11 of the extremity is sufficient to 95 appreciably weaken or impair the strength of the jaws, while it renders the tool adaptable for most or all of the uses to which the ordinary hand vice is adapted. By reference to Fig. 5 it will be noted that a workpiece W clamped in an inclined position in the jaws of the pliers requires to project only a relatively small extent above the beveled corners 11 for the action of the file thereon, since the beveled edge 12 affords 100 clearance to permit the file F or other tool to be adjusted through considerable angles 105 110

with respect to the work. My invention also contemplates the provision of suitable means engageable with the handles for holding the jaws clamped upon a workpiece without manual effort. For this purpose I show a threaded stem 13 pivoted at 14 to one of the jaws and equipped with a knurled nut 15 engageable with the outer side of the other handle, whereby upon setting up this nut, 10 the jaws may be clamped upon, and held engaged with a workpiece. The handle 10^a with which the nut engages may have a hole therethrough to receive the stem 13, and this hole may if desired be extended to the end 15 of the handle as a slot 16 permitting the stem to be swung outward away from the handle 10^a. I also preferably provide means whereby the stem 13 may be yieldingly held within the curved inner side of the 20 handle 10^b, it being understood that the handles of the pliers are preferably curved in cross section as is usual in this type of tool. For this purpose I show a spring clip socket 25 17 fixed in the handle in position to receive and snap over the extremity of the stem 13 as it is pressed thereinto. While I herein show the stem 13 as applied near the ends of the handles, it will be understood that this is merely illustrative and that this stem may 30 be located farther inward of the handles, i. e. nearer the pivot thereof in cases where it is desired to provide for a wider jaw opening. Also, the stem 13 may be made of 35 different lengths according to the extent of opening of the jaws for which it is desired to provide, i. e. the tool may thus be made adaptable for a larger range of sizes of workpieces at will. In these as well as in other respects the present embodiment is to 40 be understood as merely illustrative and not restrictive, reference being had to the appended claims rather than to the foregoing

description to indicate the scope of the invention.

Having described my invention, what I 45 claim as new and desire to secure by Letters Patent is:

1. A hand tool of a pliers type having clamping jaws with corner extremities beveled off at one side thereof and with an 50 edge of one jaw extending backward a substantial distance from such beveled corner, also beveled off to afford clearance for an operating tool.

2. A hand tool of a pliers type comprising jaws mounted for parallel movement with corner extremities thereof beveled off at one side and with an edge of at least one 55 jaw extending backward from said beveled corner, also beveled off to afford clearance 60 for an operating tool.

3. A hand tool of a pliers type comprising clamping jaws presenting opposed relatively extended parallel clamping faces, with said jaws having the corner extremities 65 thereof beveled at one side and with an edge extending backward from said beveled corner, also beveled off on at least one jaw to afford clearance for an operating tool.

4. A hand tool of a pliers type comprising opposed jaws presenting extended clamping faces adapted to hold a workpiece between them, and a threaded stem pivoted to one of the handle members and having a nut engageable with the other handle member 70 to hold the jaws clamped upon a workpiece, the handle member to which said stem is pivoted equipped with a clip adapted to hold said stem yieldably in inoperative position within said handle member.

In testimony whereof, I have signed my name to this specification.

FRANCIS H. WILLIAMS.
